UNITED STATES PATENT OFFICE

RALPH M. KEELE, OF SAN FRANCISCO, CALIFORNIA, ASSIGNOR, BY MESNE ASSIGNMENTS, TO DUART MANUFACTURING CO. LTD., OF SAN FRANCISCO, CALIFORNIA

HAIR WAVING APPARATUS

Application filed April 27, 1931. Serial No. 533,135.

This application relates generally to hair waving apparatus of the croquinole type, in which a flat strand of hair is wound or coiled about a curler or mandrel.

5 In croquinole type of hair waving apparatus it is common practice to wind a flat strand of hair upon a curler or mandrel, after which hot vapors are applied to the coiled hair to impart permanency to the wave. The 10 winding may begin from the tip of the flat strand, as in standard croquinole apparatus, or it may commence from an intermediate portion of the strand as disclosed in my copending application Serial No. 511,006, filed 15 January 24, 1931. In either case it is convenient to have some means for clamping the flat hair strand to the curler or mandrel, as the winding operation is commenced. In standard croquinole apparatus it is common 20 to provide the curler with a spring clip or finger under which the tip of the strand is engaged before the winding operation is started. Such clamping means is subject to the disadvantage that it somewhat distorts the 25 coils of hair, so that undesired kinks may be formed in the hair as finally waved. As far as I am aware no clamping means of any character has been utilized in conjunction with a slotted rewaving type of curler or 30 mandrel such as disclosed in my copending application Serial No. 511,006.

It is an object of the present invention to devise an improved type of hair engaging or clamping means for use in combination 35 or in conjunction with a curler or mandrel of the croquinole type.

It is a further object of the invention to devise an improved type of rewaving curler of the croquinole type, which is characterized 40 by the use of means for engaging the flat strand of hair as it enters the slot of the curler.

Further objects of this invention will appear from the following description in which 45 the preferred embodiment of the invention has been set forth in detail in conjunction with the accompanying drawings. It is to be understood that the appended claims are to be accorded a range of equivalents consistent with the state of the prior art.

Referring to the drawings:

Figure 1 is a view, partly in cross section, illustrating the mode of operation of a rewaving curler of the type disclosed in my copending application, Serial No. 511,006, 55 with the present improvement applied.

Figure 2 is a plan view of the combing tool utilized in conjunction with the apparatus of Figure 1.

Fig. 3 is a plan view of my improved rewaving curler illustrating the position of the flat hair strand entering the slot of the same.

Fig. 4 is a cross sectional detail illustrating the pivotal connection between the hair 65 engaging and clamping finger and the curler body.

Fig. 5 is a view similar to Fig. 4, but illustrating the hair clamping or engaging finger in a position in which it engages the hair 70 strand and overlies the slot in the curler.

Fig. 6 is a view similar to Fig. 3, but illustrating the hair engaging or clamping finger in a position to clamp a hair strand to the curler.

Fig. 7 is a view illustrating my improved curler applied to a protector.

Fig. 8 is a cross sectional detail taken along the line 8—8 of Fig. 5.

Fig. 9 is a view similar to Fig. 1, but illustrating a standard type of croquinole apparatus to which my invention is applied.

Fig. 10 is a cross sectional detail taken along the line 10—10 of Fig. 9.

Fig. 11 is a cross sectional detail taken 85 along the line 11—11 of Fig. 9.

Fig. 12 is a cross sectional detail taken along the line 12—12 of Fig. 9.

Referring first to the rewaving type of apparatus illustrated in Figs. 1 to 8 inclusive, 90 10 represents a two part protector clamp engaged upon a flat strand 11 of hair, adjacent the scalp. Spring clips 12 are carried by the end portions of protector 10. This protector is substantially the same as that disclosed in my copending application 511,006.

The curler 13 can be conveniently made of light metal such as aluminum, and includes an intermediate portion 14 upon which the strand of hair can be wound, and substan- 100

tially cylindrical end portions 16 adapted to engage the spring clips 12. Annular shoulders 17 confine the hair being wound to the intermediate portion 14, while annular shoulders 18 are formed on the ends of the curler.

A longitudinal passageway or opening 21 extends substantially the entire length of the intermediate portion 14, and is open thru one end of the curler as shown in Fig. 1. Extending substantially coextensive with opening 21, there is a longitudinal slot 22 within which a flat strand of hair can be disposed. In order to clamp a strand of hair entering or disposed within slot 22, I provide a finger 23 made of a relatively stiff springy wire. This finger is pivotally retained to the main body of the curler by having its one end provided with a laterally bent portion 24, which extends into an aperture 26 provided in one end portion of curler 13, as shown in Fig. 4. An enlarged head 27 is provided upon laterally bent portion 24, and interposed between this head and an opposed shoulder formed on the curler 13, there is a compression spring 28. Thus the pivotal axis of this connection is normal to the longitudinal axis of the curler and to the finger 23, and it also intersects the longitudinal axis of the curler. Finger 23 can thus be swung to an engaged position in which it overlies slot 22, or it can be swung outwardly to an out of the way position as shown in Fig. 3. In order that finger 23 in its engaged position may not greatly alter or modify the contour of the intermediate portion 14 of the curler, the finger is preferably oval shaped as shown in Fig. 8, and where the curler comes into contact with the retaining finger 23 along the intermediate portion 14, the curler is preferably slightly beveled as indicated at 31 in Fig. 8. Likewise that end portion of the curler adjacent the end of slot 22 is preferably notched as indicated at 32 to receive the outer end of finger 23. When finger 23 is sprung into engaged position as shown in Fig. 6, it projects a short distance beyond the adjacent end of the curler, thus permitting its ready manual engagement for moving the same to disengaged or out of the way position.

In utilizing the apparatus described above, I preferably employ some suitable form of tool for combing out the hair strand. The tool illustrated in Fig. 2 can be utilized for this purpose, and has been described in detail in my copending application, Serial No. 511,006. This tool is made like a pair of pliers, being provided with handles 33 and opposed elongated members 34 and 36. Member 34 is provided with projecting comb teeth 37 which are received in openings 38 formed in member 36, when members 34 and 36 are in closed position.

Assuming now that a flat strand of hair has been clamped by protector 10, this strand is engaged by the combing tool of Fig. 2 ad-

jacent the protector 10, and the tool moved outwardly to comb out the strand. When the strand has been combed out a distance from the protector 10 corresponding to the length of strand portion to be waved, a curler 13 is positioned adjacent the combing tool as shown in Fig. 1 so as to cause the hair strand to enter slot 22, with the end portion of the strand extending out thru the opening 21. Retaining finger 23 is now swung to engaged position as shown in Fig. 6, and then the combing tool of Fig. 2 can be removed from the strand. When in engaged position finger 23 exerts a clamping action along the entire width of the hair strand, and the operator by grasping the ends of the curler, can now rotate the curler to advance the same toward the protector, and to wind or coil the strand of hair upon the curler with proper tension. When in proximity with the protector, the curler is forced into engagement with spring clips 12, and then further tension can be applied to the hair by further rotation of the curler. To effect such further tensioning a slot 41 is shown formed in the end of the curler, and this slot can be readily engaged by a suitable key or wrench. After final positioning upon the protector as shown in Fig. 7, a suitable pad can be applied over the wound hair, and an electrical heater clipped over the entire assembly. After a waving operation the curler is disengaged from the protector, and the hair unwound, after which the strand is disconnected from the curler by swinging retaining fingers 23 to an out of the way position.

In Figs. 9 to 12 inclusive I have shown a curler intended to be used where a wave is to be imparted only to the entire length of the hair strand. In this case the mandrel 42 is solid, and the retaining finger 43 (corresponding to the finger 23 of Figures 1 to 8 inclusive) likewise has a laterally bent end portion 44 extending through opening 46 in the mandrel. The end of portion 44 likewise has a head 47 engaged by a compression spring 48. The medial portion of the mandrel along one side thereof is provided with a flattened surface 49 to accommodate finger 43, and this flattened surface extends to one end of the mandrel (Figures 9 and 12) as the bottom of a notch 51. The use of such a mandrel is shown in Figure 9. The tip portion of a flat hair strand 11 is laid across surface 49, and clamped to the mandrel by slipping finger 43, to the position shown in solid lines in Figure 9. This hair is then wound about the mandrel and the mandrel engaged with protector 10.

I claim:

1. In a hair waving apparatus, a curler or mandrel upon which a flat strand of hair can be wound, and means for clamping the strand along one side of the mandrel, said means including a finger having one end thereof piv-

totally connected to one end portion of the mandrel, the pivotal connection being on an axis normal to the finger and to the axis of the mandrel and intersecting the axis of the mandrel, the other end portion of the mandrel having a notch in its periphery adapted to receive and retain said finger.

2. In a hair waving apparatus, a curler or mandrel upon which a flat strand of hair can be wound, and means for clamping the strand along one side of the mandrel, said means including a finger having a laterally bent portion on one end thereof, said mandrel having an aperture near one end thereof intersecting the mandrel axis and extending substantially at right angles thereto, said bent portion having an enlarged head and being positioned within said aperture, and a coiled spring interposed between said head and a shoulder on the mandrel, the other end portion of the curler having a notch in its periphery into which the finger is adapted to be snapped and retained when swung into a position along one side of the mandrel.

25 3. In a hair waving apparatus of the re-wave type, a mandrel upon which a flat strand of hair can be wound, said mandrel having a longitudinal opening and slot whereby the strand can be received in said slot with the end portion of the strand extending out said opening, and means mounted upon the mandrel for clamping the strand to the mandrel adjacent said slot.

4. In a hair waving apparatus of the re-wave type, a mandrel upon which a flat strand of hair can be wound, said mandrel having a longitudinal opening and slot whereby the strand can be received in said slot with the end portion of the strand extending out said opening, and means for clamping the strand to the mandrel adjacent said slot, said means including a retaining finger adapted in one position thereof to overlie said slot.

45 5. In a hair waving apparatus of the re-wave type, a mandrel upon which a flat strand of hair can be wound, said mandrel having a longitudinal opening and slot whereby the strand can be received in said slot with the end portion of the strand extending out said opening, and means for clamping the strand to the mandrel adjacent said slot, said means including a retaining finger pivotally connected to said mandrel and adapted to be swung into a position to overlie said slot and engage said strand.

6. In a hair waving apparatus of the re-wave type, a mandrel upon which a flat strand of hair can be wound, said mandrel having a longitudinal opening and slot whereby the strand can be received in said slot with the end portion of the strand extending out said opening, and means for clamping the strand to the mandrel adjacent said slot, said means including a spring wire re-

taining finger, and means for pivotally connecting said finger to the mandrel, the axis of the pivotal connection being normal to the length of the finger and to the axis of the mandrel, and intersecting the axis of the mandrel.

In testimony whereof, I have hereunto set my hand.

RALPH M. KEELE.
